ATHLETIC SHOE CALK

Fred C. Phillips, Stoughton, Mass.

Application August 7, 1947, Serial No. 766,959

2 Claims. (Cl. 36—59)

1

This invention relates to an athletic shoe calk adapted to screw into a socket member set in the sole or heel of the shoe, and to a method of making such calks. It is an object of the invention to provide a calk which is of a type described and illustrated in Patent No. 1,827,514, granted to Daniel J. Golden on October 13, 1931, but which is superior in construction and can be more easily and cheaply manufactured. Calks of this description are made with a plate or disk adapted to bear against the tread surface of a shoe. A threaded stud projects axially from one face of the plate to engage a threaded socket member embedded in the shoe sole or heel. Projecting axially from the other face of the plate is the ground-penetrating portion of the calk which may be a tapered spike or any other desired form.

According to the present invention, the calk is made in two separate parts which are assembled to complete the structure. One of the parts is the disk which may conveniently be stamped from a sheet of suitable metal such as soft steel. The other part is the axial member which includes the threaded stud and the tapered spike. This second member is preferably case-hardened to increase the strength and wearing qualities of the spike.

For a more complete understanding of the invention, reference may be had to the following description thereof and to the drawing, of which—

Figure 1 is a perspective view, partly broken away, of a blank from which the plate member is made;

Figure 2 is a perspective view of the axial member of the calk;

Figure 3 is a transverse, sectional view of the finished plate;

Figure 4 is a sectional view of the assembled calk; and

Figure 5 is a fragmentary, sectional view of a shoe sole on which a complete calk is mounted.

The calk embodying the invention consists of two separately made members, one of which is a disk or plate 10 which can be stamped from a sheet of suitable material such as soft steel, as shown in Figure 1. At the same time, a central aperture 12 and two small holes 14 may be punched in the blank, the holes 14 being for the purpose of receiving the pins of a pin wrench or similar tool by which the calk is screwed into place on a shoe sole, as hereinafter described.

After the flat blank for the plate 10 has been stamped from a sheet, it is swaged by the use

2

of a suitable die so as to give it a dished form, as indicated in Figure 3. As a result of this swaging operation, the blank assumes a saucer shape having a raised rim 16 which presses into the shoe sole when the spike is secured thereto. The swaging operation also serves to deform the side walls 18 of the central aperture 12 so that these side walls are given a slight taper.

The axial member 20 of the calk, which is illustrated in Figure 2, can be conveniently made from rod stock by the use of suitable turning tools and a screw threading die. This member comprises a central portion 22 which is slightly tapered and is of a size to enter the aperture 12 with a drive fit. The edge of the portion 22 is preferably knurled with sharp ridges which cut channels in the wall 18 of the aperture 12 when the member is driven into place in the aperture 12.

20 The upper part of the axial member 20 is a screw-threaded stud 24 adapted to be screwed into a threaded socket 26 in an anchoring member 28 which may be mounted in the outsole 30 of a shoe, as indicated in Figure 5. Immediately 25 below the central portion 22 the axial member 20 has a flange 32 of somewhat larger diameter than the portion 22 so that a shoulder 34 is formed which engages against a lower face of the plate 10 when the calk is assembled. Projecting downward below the flange 34 is the ground-penetrating element 36 which may be of any desired shape, a frusto-conical shape being shown in Figure 4. The axial member 20 is preferably case-hardened after it has been suitably 35 shaped, to give it superior wearing qualities. This hardening process also enables the knurling on the central portion 22 to cut more readily into the wall 18 of the aperture 12 so that the two parts of the calk are thus locked against relative rotation.

When the threaded stud 24 is screwed into the socket 26, it is evident that the resulting upward tension on the axial member 20 tends to press the shoulder 34 against the plate 10 and to keep the two parts of the calk from separating or working loose.

I claim:

1. A calk for an athletic shoe or the like, comprising a metal plate having a central aperture, and an axial member of harder material than that of the plate extending through said aperture, said member having a knurled central portion engaging the walls of said aperture with a driving fit, said member having a flange adjoin-

ing said central portion engaging the lower face of the plate around the aperture, said member also including a tapered spike projecting down from said flange and a threaded stud projecting up from said central portion.

2. A calk for an athletic shoe or the like, comprising a disk with a central aperture, and an axial member extending through said aperture, said member having a screw-threaded portion at its upper end, a knurled central portion tapering upwardly and engaging the walls of said aperture with a drive fit, a flange below said knurled portion having a shoulder bearing on the lower face of the disk, and a downwardly tapering spike portion at its lower end. 15

FRED C. PHILLIPS.
